PROJECTION-LAMP.

1,210,676.

Specification of Letters Patent. Patented Jan. 2, 1917.

Application filed May 12, 1915. Serial No. 27,698.

To all whom it may concern:

Be it known that I, JAMES M. NAUL, a citizen of the United States, residing at and whose post office address is 747 Kensington 5 avenue, Plainfield, New Jersey, have invented certain new and useful Improvements in Projection-Lamps; and I do hereby declare the following to be a full, clear, and exact description of the invention, such as will enable others skilled in the art to which it 10 pertains to make and use the same.

In projection lamps, the reflecting surfaces are usually of parabolic, spherical or elliptical form, and may be associated with 15 condensers or other lenses and also with supplementary reflectors, the object being to project an intense beam of light of cylindrical or conical form.

In projection lamps for stationary work 20 and for moving vehicles such as automobiles, motor boats, locomotives, electric cars, etc., the reflecting surface is generally that generated by a parabola in rotation on the axis of projection of the lamp, and consequently the reflecting surface has a single 25 focal point from which the light rays emanating therefrom and striking the reflecting surface are projected in lines parallel to the axis of the lamp, the light rays emanating 30 from all other points of the light-giving medium being projected at an angle thereto. These angularly projected rays are subtracted 35 from the cylindrical beam and thus reduce its intensity. Those rays which are directed downwardly may be desirable for illuminating the way directly ahead of the vehicle, although the way is usually illuminated too brilliantly and too close to the vehicle; and those rays which are directed 40 sidewise and upwardly, usually represent a total loss in the light-giving effectiveness of the lamp. Since it is impossible as a practical matter to concentrate the light-giving medium at a single point, even when an incandescent lamp is used for the purpose, 45 these reflector headlights project a cylindrical beam of reduced intensity and diffused rays which in most part are wasted.

The object of my invention is to produce 50 a forwardly directed beam of light of much intensity, and I do this in a reflector headlight by providing a reflecting surface which is not generated by a curve in rotation as heretofore, but is formed of curves having 55 foci at slightly separated points which are

contained in the light-giving medium. In this way, light rays emanating from a plurality of points in the arc, flame or filament forming the light-giving medium, are projected in a forwardly directed beam of cylindrical or other form, while the projected rays outside of the beam may be directed in such manner as to illuminate the way with greater effectiveness.

In the preferred form of my invention for headlights for moving vehicles, I use a reflecting surface formed by parabolas of gradual differing focal length and having their foci wholly contained in an axially arranged filament of an incandescent lamp. 60 The projection therefrom consists of a comparatively intense, axially-directed, cylindrical beam, and angularly directed rays which effectively illuminate the way with diffused light.

It will be observed that in headlights having the reflecting surface generated by a parabola in rotation on its axis, the rays emanating from the single point of the light at the focus of the parabola are projected in 65 an axially-directed cylindrical beam, while in my preferred form of lamp, all the rays from the entire filament which strike the reflecting surface at the parabolic curves having their foci at the points of emanation go 70 into the axially-directed cylindrical beam.

In the accompanying drawings illustrating the preferred embodiment of my invention in application to a reflector headlight of the electric type, especially adapted for 75 moving vehicles as an example, Figure 1 is a vertical section along the axis of the lamp; and Fig. 2 is a front elevation thereof.

The projection lamp shown in the drawings has a front cover of glass 1 permanently 80 fastened over the front of the reflector 2 by the retaining rim 3. It also has an incandescent lamp 4 fixed in a socket 5 which also carries the reflecting portion 6 normally conforming to the contour of the reflector. 85 The terminal connector 7 provides the electric circuit connection with the filament of the lamp, and the arrangement is such that the reflector 2, together with the incandescent lamp 4, can be swung on a hinge (not 90 shown) between the retaining rim 3 and the lamp housing 8, so as to expose the rear of the reflector for the replacement of the incandescent lamp. The foregoing devices are 95 well known in the art.

The reflector 2 is formed of a series of parabolas of gradually differing focal lengths. The parabola A—A, lying in the vertical plane containing the axis of projection of the lamp, has the least focal length, 5 and the parabola B—B, lying in the horizontal plane containing said axis, has the greatest focal length, while the focal lengths of the intermediate parabolas gradually vary between these two. Furthermore, 10 the axes of the parabolas coincide with the axis of the headlight. Thus, the focus of the parabola A—A is at a , the focus of the parabola B—B is at b , and the focus of the intermediate parabola C—C is at c , all lying 15 in the axis of projection and also in the axis of the headlight. The filament 9 of the incandescent lamp is straight and is positioned at the axis with its illuminating part extending from one limiting focus a to the other b , thereby containing the foci of all 20 the parabolas forming the reflecting surface. All the light rays which emanate from a and strike the parabola A—A are projected 25 axially therefrom, as are all those which emanate from any other point of the filament and strike that parabolic curve of the reflecting surface which has its focus at the point of emanation. In this way, an intense 30 cylindrical beam is projected axially of the lamp. These axially-directed rays are indicated in Fig. 1 by broken lines.

The rays which strike the reflecting surface at a parabolic curve not having its 35 focus at the point of emanation are projected in divergent lines, angularly disposed to the axis of the lamp, those directed downwardly illuminating the road. Furthermore, those rays which proceed forwardly

from the filament, without striking the reflecting surface, are mostly divergent, but 40 owing to the fact that the filament 9 is horizontal, their number is comparatively small. I have found that this arrangement results in a projection which is composed of an intense cylinder of light axially directed, and 45 of such an amount of diffused light, that the road is nicely illuminated and at a suitable distance ahead of the vehicle. It will be observed that the base of the lamp is of elliptical form with the major axis capable of 50 such disposition that the headlight may be nicely accommodated on an automobile.

Having thus described my invention, what I claim is:

1. In a projection lamp, a reflecting surface made up of curves which are different along the intersection with planes containing the axis of projection and which have a plurality of foci, and a light giving medium containing said foci. 55

2. In a projection lamp, a reflecting surface made up of parabolas which, at the intersection with different planes containing the axis of projection, have different focal lengths, and a light giving medium containing 60 the foci of said parabolas. 65

3. In a projection lamp, a reflecting surface in the form of an elliptic paraboloid, and a light giving medium containing the 70 foci of the parabolas in said surface.

In testimony whereof I affix my signature, in presence of two witnesses.

JAMES MYRVEN NAUL.
